J. H. Weston, draughtsman

UNITED STATES PATENT OFFICE.

ELMO M. CHANDLER, OF SOUTH NORFOLK, VIRGINIA, ASSIGNOR, BY MESNE ASSIGNMENTS, TO AUTOMATIC SPRINKLER COMPANY OF CANADA, LIMITED, OF TORONTO, ONTARIO, CANADA.

SPRINKLER-HEAD.

1,250,281.

Specification of Letters Patent.

Patented Dec. 18, 1917.

Application filed March 9, 1917. Serial No. 153,760.

To all whom it may concern:

Be it known that I, ELMO M. CHANDLER, a citizen of the United States, and resident of South Norfolk, in the State of Virginia and United States of America, have invented 5 certain new and useful Improvements in Sprinkler-Heads, of which the following is a full, clear, and exact description.

This invention relates to improvements in 10 sprinkler heads, and the object is to provide a sprinkler head which may be easily and cheaply manufactured, and will consist of a small number of parts.

A further object is to provide a sprinkler 15 head having the strut thereof so arranged that the fusible metal holding the same in operative position is subjected to the minimum of stress, and therefore is not liable to perish or yield under stress at temperatures lower than that for which it is designed.

A still further object is to provide means for obtaining a substantial bond between the strut parts by means of the fusible metal.

Another object is to provide a strut so 25 constructed that the fusible metal is relieved as far as possible of all stress arising from accidental blows or pressure.

A large number of sprinkler heads have been produced in the past which, however, 30 have the disadvantage that the fusible material holding the strut in operative position is subject to such great stress that the metal perishes in a comparatively short time, or if it does not perish, flows under the stress 35 at temperatures lower than that at which the head is designed to blow, thus causing a loosening and leakage at the valve. It has also been found difficult to obtain a good bond between the strut parts by means of 40 the fusible metal.

According to this invention, the strut is composed of three members, two of which are pivotally connected out of the line of thrust, and a third or key, mounted in one 45 of the first members and exerting considerable leverage over the other to hold them in predetermined position despite thrust. Parts of the members are in superposed relation, and they may be provided with 50 flanges to embrace and hold the superposed member against displacement by accidental blows or pressure. The key member has an apertured lip, through and around which the fusible material extends, thus securing 55 a very good hold.

In the drawings which illustrate the invention:

Figure 1 is a front elevation of a sprinkler, according to this invention.

Fig. 2 is a sectional view on the line 2—2, 60 Fig. 1.

Fig. 3 is a front elevation showing the strut members separated.

Referring more particularly to the drawings, 11 designates a body having a threaded 65 neck 12 adapted to screw into the pipe system, and a seat 13 for the reception of a valve 14, which with the gasket 15 normally closes the passage 16 through the body and neck. The body is provided with a yoke 17, 70 which carries a deflector 18 in the usual manner, and a strut holding screw 19, which when finally inserted is retained by the pin 20.

The strut consists of three members 21, 22 75 and 23, and the fusible holding material, designated 24. The member 21, which for descriptive purposes may be called the post, is provided at one end with a recess 25, in which the raised center of the valve rests, 80 and with a hook 26. The opposite end 27 of the post extends nearly to the point of the holding screw 19, and the post itself lies out of the common axial line running through the center of the valve and holding 85 screw, as is clearly shown in Fig. 2. The lever member 22 is provided at one end with a recess 28 to receive the point of the holding screw, and with a further recess 29 to receive the point of the post, which latter is 90 reduced in width so as to enter the recess, as clearly shown in Fig. 3. The arm 30 of the lever member lies against the post in a recess 31, which is formed by side flanges 32 on the post, and a transverse step 33 adjacent 95 the hook 26. It will be clearly seen from Fig. 2 that the free end of the lever is flush with the surface of the post, so that the key 23, which is seated at one end in the hook 26, will engage the surfaces of both the post 100 and lever. This key extends considerably beyond the end of the lever, so that the end of the lever being considered as the fulcrum point, it is obvious that the free extremity 105 of the key will have considerable leverage over the end of the lever. This free extremity of the key is provided with an aperture 36, and is in addition turned outwardly or away from the lever. The key may be held against displacement in an 110

edgewise direction by means of flanges 37 on the arm 30 of the lever, and its end retained in the hook 26 by reason of the hook extending around the edges of the key, as indicated in Figs. 1 and 3, so that the key seat in the post may be described more properly as a recess than as a hook. It will be understood that while it is preferred to use the method of inserting the end of one member in the other as described, and also the holding flanges, that the device may be constructed without these, and will operate as satisfactorily, except that it will not be as thoroughly proof against accident.

15. In manufacture of the sprinkler heads, the three members of the strut are assembled and secured by means of the fusible metal 24, which extends over and through the end of the key, and is retained by the key end in sufficient body to have the desired strength and bonding effect. The strut is now inserted in the yoke, one end being seated on the valve and the other engaged by the pin 19, which is screwed down sufficiently tight to hold the valve on its seat against the pressure which the head is designed to withstand. The head of the screw beyond the yoke is cut off and burred over in the usual manner, and the screw further secured by the pin 20. It will be seen in Fig. 2 that the strut is in effect jointed at the end of the post, which joint is out of line with the points of support at the ends of the strut, so that the pressure of water on the valve has a constant tendency to fold up the strut on its joint. This is resisted by the leverage of the key and the leverage in the long arm 30 of the lever, as will be readily seen.

30. When the head is subjected to the tem-

perature at which it is designed to blow off, the metal 24 fuses and releases the key, which in turn releases the lever arm 30, and permits the strut to fold up under the fluid pressure on the valve 14.

45

By setting the end of the post into the lever and the end of the key into the post, and also by having the key and lever arm embraced by flanges, as previously described, the parts are mechanically held 50 against separation by accident.

Having thus described my invention, what I claim is:-

1. In a sprinkler head, a body, a yoke, a valve, a strut held in compression between 55 the yoke and valve, said strut comprising a pair of members hingeably connected out of line with their points of support on the yoke and valve, a key engaging at one end in one member and overlapping the other member and holding the members in operative position, said key having its free end apertured and directed away from the strut, and a mass of fusible material extending over 60 said outturned key end and through the 65 aperture thereof and securing the key to the strut members.

2. In a sprinkler head, a body, a yoke, a valve, a jointed collapsible strut held in compression between the yoke and valve, a 70 key holding the strut against collapse, a mass of readily fusible material holding the key, and flanges on the strut members holding the members and key against accidental separation and relieving the fusible material of stress due to accidental blows or pressure.

In witness whereof, I have hereunto set my hand.

ELMO M. CHANDLER.
